V. C. GRAVES,
PLATE LIFTING DEVICE,
APPLICATION FILED AUG. 8, 1919.

1,337,450.

Patented Apr. 20, 1920.

UNITED STATES PATENT OFFICE.

VELMA C. GRAVES, OF YAKIMA, WASHINGTON.

PLATE-LIFTING DEVICE.

1,337,450.

Specification of Letters Patent. Patented Apr. 20, 1920.

Application filed August 8, 1919. Serial No. 316,133.

To all whom it may concern:

Be it known that I, VELMA C. GRAVES, a citizen of the United States, residing at Yakima, in the county of Yakima and State 5 of Washington, have invented certain new and useful Improvements in Plate-Lifting Devices, of which the following is a specification.

This invention relates to kitchen utensils, 10 and more particularly to lifters for plates, pans and the like.

The object of the invention is to provide a simple, efficient and cheaply constructed lifter, which may be used for lifting pies 15 and the like from a hot oven without danger of burning the hands or arms and which may also be used for lifting articles outside the oven.

With the foregoing and other objects in 20 view, which will appear as the description proceeds, the invention resides in the combination and arrangement of parts and in the details of construction hereinafter described and claimed, it being understood that changes 25 in the precise embodiment of the invention herein disclosed may be made within the scope of what is claimed without departing from the spirit of the invention.

The accompanying drawing represents a 30 perspective view of this improved lifter shown open in full lines and closed in dotted lines.

The lifter 1 constituting this invention is composed of two strands of heavy wire, one 35 of which is rectilinear throughout a portion of its length to form a body member 2, and one element of a handle 3, said wire being looped to form the other member of said handle. The member 3^a of the handle is 40 offset inwardly as shown at 4 and twisted around the member 2 at a point intermediate of its ends as shown at 5. This wire is then extended and bent to form a substantially U-shaped rigid jaw comprising a 45 laterally extending leg 6 having an incurved portion 7 and an outwardly bowed portion 8. The wire is then extended in a plane substantially at right angles to the member 6 to form a cross bar 9 which 50 merges at its outer end into a leg or arm 11 connected thereto by an outbowed portion 10, said leg 11 being similar to the leg 6 of the rigid jaw. The free end of leg 11 is bent to form an eye 12 through which passes 55 the outer end of the member 2 and which is

secured to said member by a nut 13 or other suitable fastening.

A movable jaw 15 is hingedly carried by the member 2 and is substantially U-shape in form, composed of a single strand of wire 60 bent to provide a pair of spaced legs 16 connected through the medium of a cross bar 17. These legs 16 are bowed outwardly adjacent their connection with bar 17 as shown at 18 and their terminals are bent to form 65 eyes 19 through which the member 2 passes loosely, said eyes being arranged inside the legs 6 and 11 of the rigid jaw 14.

In the use of this device, when it is desired to lift a culinary vessel such as a pie 70 plate or the like, the jaw 15 is swung to an open position and engaged under the flange of the vessel to be lifted. The user then turns the handle 3 in a direction away from the movable jaw, thus moving the rigid jaw 75 14 into clamping engagement with the opposite diametric point of the flange of the vessel to be lifted. It will thus be seen that by this operation, a firm gripping action of the jaws with the vessel is obtained. 80

The device is extremely simple in construction and the looped handle, while affording a reliable grip on the device, also provides means for suspending the article 85 from a nail or other suitable support.

From the foregoing description, taken in connection with the accompanying drawings, the advantages of the construction and of the method of operation will be readily apparent to those skilled in the art to which 90 the invention appertains and while I have described the principle of operation of the invention together with the device which I now consider to be the best embodiment thereof, I desire to have it understood that 95 the device shown is merely illustrative and that such changes may be made as are within the scope of the claimed invention.

Having thus fully described my invention, what I claim as new and desire to secure by Letters Patent, is:—

A lifter of the class described composed of two strands of heavy wire, one of which is rectilinear throughout the greater portion of its length to form a single strand body 105 and one member of a handle loop, said member and body being in longitudinal alignment, said strand being bent at the outer end of said handle member and extended inwardly and spaced laterally from the first 110

mentioned handle member to form the other handle member, said strand being wrapped around the inner end of the first mentioned handle member and bent to form a laterally 5 extending U-shaped jaw at one side of said body, the legs of said jaw being bowed outwardly adjacent the cross-bar of the jaw, the front leg of said jaw having an eye encircling the front end of said body; 10 the other strand being in the form of a U-shaped jaw having eyes at free

ends of its legs hingedly engaged with said body adjacent the inner sides of the legs of the other jaw, and its legs bowed outwardly adjacent its cross-bar.

15

In testimony whereof I affix my signature in presence of two witnesses.

VELMA C. GRAVES.

Witnesses:

DOROTHY JACOBS,
GUY O. SHUMATE.
